TYPEWRITING MACHINE

William F. Helmond, West Hartford, Conn., assignor to Underwood Elliott Fisher Company, New York, N. Y., a corporation of Delaware

Application August 15, 1935, Serial No. 36,272

14 Claims. (Cl. 197—138)

This invention relates to the paper-feed or pressure rolls that are associated with the platen-roll of a typewriter.

A feature of the invention is the provision, in combination with spring-means for the bottom feed-rolls, of novel devices designed to facilitate adjustment of said spring-means to regulate the bottom feed-roll pressure, and to gain other advantages.

10 A further feature of the invention resides in an improved booster-spring device usable at will, as when typing a stiff work-sheet, for applying to the bottom feed-rolls, spring-pressure which is additional to or above the regular spring-pressure.

15 Two sets of main feed-rolls, front and rear, at the bottom of the platen are carried by means of rocker-arms. The rocker-arms, for each bottom feed-roll set, are connected by a cross-rod spaced from the rocker-arm axis. A draw-spring, for pressing the bottom feed-rolls against the platen, is connected across the cross-rods and is therefore common to both sets of bottom feed-rolls. One of the rocker-arm-connecting rods is notched by means of a screw-thread provided thereon. One end of the draw-spring is anchored in and is differentially locatable by means of said screw-thread notches for adjusting the spring-pressure, and the other end of the draw-spring may be fixed to the other cross-rod.

20 The draw-spring will be at least tension when it extends squarely across the rocker-arm-connecting cross-rods. By slanting the spring across the cross-rods its tension will be increased. This 25 slanting of the spring, for adjustment of the feed-roll pressure, may be effected differentially by shifting the screw-thread-engaging end of the spring to different notches as by merely drawing the spring-end out of one notch of the screw-thread and passing it to another notch. The adjustment may also be effected by turning the 30 threaded cross-rod, the thread then acting to move the draw-spring end along the cross-rod, like a nut held against rotation, to slant the 35 spring more or less, depending upon the direction and extent of turning the threaded cross-rod. Additional locking devices are not necessary to maintain the draw-spring in its adjusted position since the adjustable draw-spring end cannot of 40 itself creep along the thread of the cross-rod, nor can the threaded cross-rod turn of itself since it is frictionally held by the tension of the draw-spring.

45 For applying more than the regular spring-pressure upon the feed-rolls, as when a stiff

work-piece is to be fed around the platen, an extra or booster-spring device is used and is arranged to apply the extra spring-pressure to both sets of bottom feed-rolls. To this end a leaf or bar spring spans the aforesaid rocker-arm-connecting cross-rods to press upon the latter. A spring-flexing finger may be brought into play manually by means of a handle to bear upon said leaf-spring at a point between said cross-rods and flex said spring, and thereby cause 10 it to put additional spring-pressure upon both sets of bottom feed-rolls by way of said cross-rods.

15 Withdrawal of said finger by means of said handle will remove the extra spring-pressure from the bottom feed-rolls. Said finger may be made resiliently yieldable, as by mounting it upon a resiliently yieldable support, for the purpose that when the bottom feed-rolls are cast off, said finger, if it be effectively positioned, may yield 20 and thereby obviate excessive flexing of the already flexed booster-spring.

25 The booster-spring may press upon the rocker-arm-connecting cross-rods intermediately of the ends of the latter, so that it may act uniformly upon the bottom feed-rolls. In order that the primary or adjustable draw-spring device may also act uniformly upon the bottom feed-rolls two draw-springs may be used, one beyond each 30 side of the booster or secondary spring device.

Other features and advantages will hereinafter appear.

In the accompanying drawings,

35 Figure 1 is a perspective showing the platen-frame of a standard Underwood noiseless typewriter, provided with the present improvements.

Figure 2 is a view showing the draw-spring, drawn out of the groove of the threaded anchorage-shaft preparatory to setting the end of the spring into one or another groove for adjustment of the spring tension.

40 Figure 3 is similar to Figure 2, but shows the draw-spring seated in one of the grooves.

Figure 4 is a sectional side elevation, showing the novel draw-spring-devices, and the feed-45 rolls in normal positions.

Figure 5 is a plan of the platen-frame assembly, partly broken away, showing the draw-spring and booster-spring devices.

Figure 6 is a sectional view similar to Figure 4, 50 but shows in addition the booster-spring and how it is flexed to apply extra pressure to the feed-rolls.

Figure 7 is a sectional view similar to Figure 6, 55 but shows the feed-rolls cast off from the platen.

The usual Underwood platen 10 is journaled by axle 11 in ends 12, 13, of a platen-frame. Front and rear feed-rolls 14 and 15 run upon the bottom of the platen. Type-bars 16 strike the platen 10. The feed-rolls are thrown on and off the platen by rocking a cam-shaft 17.

Novel spring-tension means for the feed-rolls 14 and 15 are applied and adjusted in the following manner.

10 Tension or draw springs 19 and 20 may be caught at their forward ends in grooves 21 and 22 of a cross-rod 37, which, at its ends, is loosely connected to front feed-roll-carrying rocker-arms 23 and 24. These springs tend to lift said 15 arms, and press the front rolls up against the platen.

Attached to the rearward end of each of springs 19 and 20 is a clip-hook or eye-piece 25, with an aperture 26 in its rear end. For adjusting the 20 stretch and thereby the tension of the draw-springs 19, 20, there has been provided a novel anchorage-shaft or cross-rod 27, which may be 25 rotatively supported in rocker-arms 28, 29, which carry the rear feed-rolls 15. Said shaft 27 has screw-threaded portions to afford notches 30, 31, by means of which the eye-pieces 25 of the draw-springs may be differently spaced, along said 30 shaft 27, from the spring-ends that are fixed by the grooves 21, 22.

30 By using a hook 32, as seen in Figure 2, or pliers 33 as in Figure 1, the clips 25 of the springs are withdrawable from the notches 30 and 31, for shifts to the right or left along the shaft 27, and may be seated in any desired notch 30 or 31, to 35 slant the springs more or less across the cross-rods 27, 37 and thereby regulate their tension.

Thus either draw-spring may be adjusted individually, so that adjustment can be effected in the pressure of the front and rear feed-rolls at 40 either the right or left of the roll-system. Since each spring 19, 20 is connected to front and rear roll-carrying arms 23, 24 and 28, 29, it presses the arms upwardly about their pivots, to press the end rolls up against the platen. The springs act 45 together upon the middle rolls 14, 15. The tensioning of either spring by slanting it more in the described manner, will increase the pressure of the adjacent front and rear end rolls. Thus adjustment and correction may proceed until all rolls 50 bear equally upon the platen. Or the pressure upon one end of the platen may be made greater than upon the opposite end. Collective or omnibus adjustment may be effected by turning the shaft 27 by means of either of the easily accessible 55 screw-slotted ends 34 or 35. As shaft 27 is turned, the eye-ends 25 of the springs are adjusted by the screw-threads 30, 31 towards or away from the ends fixed in the grooves 21, 22 of cross-rod 37, thereby easing or increasing the 60 tension. The screw-threads 30, 31 are shown as being of opposite hands, so that the two springs 19, 20 may slant rightward and leftward for the purpose of neutralizing their end-thrust effects upon the cross-rods 27, 37.

65 Through this uniform collective feed-roll tensioning, there may always be a balanced or equalized feed-roll pressure. The universal adjustment can be effected, whether the original tensions of the springs 19 and 20 are even or uneven.

70 It will be seen that the two lines of feed-rolls are connected, to move simultaneously into and out of engagement, with the platen and work-sheets. This is effected by a feed-roll-release lever, not shown, having connection 18 with the 75 usual cam-shaft 17, which extends along the

platen, to control the release and restoration of the feed-roll arms and rolls.

It will be seen that a uniform and true tension can be secured on all the rolls; and a properly proportioned feed-roll pressure may be effected. 5 There is provision of right and left individual spring tension; and spring adjustment for normal feed-roll setting is secured by moving the eye-pieces 25 into selectable notches 30, 31 on rear anchorage-shaft 27. After the feed-rolls have 10 been normally set to the platen, with either even or uneven pressure, their pressure can be collectively increased or decreased by turning the dual threaded anchorage-shaft 27 in its bearings in the feed-roll-carrying arms 28, 29 which may also 15 coat with shaft-shoulders, indicated at 46, Figure 1, to retain said shaft 27 endwise.

Each of the rear feed-roll-carrying arms 28, 29 is pivoted upon a shaft 47 and has a stabilizing hub 48. The carrying arms 23, 24 for the front 20 feed-rolls 14 are also pivoted upon said shaft 47. Said pivoted shaft 47 is supported in brackets 49 on the platen-frame base 40 and is retained against endwise displacement by means of an end head 51 and an end nut 52. The feed-roll-releasing cam-shaft 17 is also journaled in the brackets 49 and is retained against endwise displacement by a collar 53 and by abutment of the side of a cam-flat-forming notch 54 of said shaft 17 with arm 55 of the front feed-roll-carrying arm 24, the 30 latter in turn abutting one of the brackets 49.

For applying extra pressure to the feed-rolls 14, 15, as for thick-card-feeding, a leaf spring 36 is used as a booster-spring and is clipped by means of a curled end 36^a, Figure 1, to the middle of anchor-shaft 27. The front end of said spring abuts the under side of the front cross-rod 37 midway thereof. This spring 36 may be normally unflexed, Figure 1, for regular feed-roll pressure, or, if extra pressure is desired, it may be flexed, 40 Figure 6, by means of a finger or cam 38, attached to a rock-shaft 41, journaled in a yieldable support 39 adjacent the finger 38. Said booster-spring-controlling rock-shaft 41 extends beyond the platen-frame end 13 to present a handle 44, 45 and is supported near its handle end by a hanger 42 secured to said platen-frame end by screw 43.

The yieldable support 39 constructed of spring metal and fastened to the platen-frame base 40 by a screw 56 forms a resilient arm having its 50 free end curled as at 39^a to form the bearing for booster-spring-controlling rock-shaft 41. Said yieldable support 39 may have on either side of the single screw 56 a downwardly-projecting holding tongue 45 engaging the base 40. 55

Upon casting off the feed-rolls 14, 15, as in Figure 7, the support 39 will yield together with the finger 38 if the latter has been operated to flex the booster-spring 36 for extra spring pressure. The yielding of the finger 38 through its 60 support 39 thus obviates excessive flexing of the already flexed booster-spring 36 when the feed-rolls are cast off. The rock-shaft 41 may be sufficiently loose in the bearing 39^a and in the hanger 42 to permit it to swivel slightly in said 65 hanger 42 in accommodation to the yieldability of said support 39. The rear set of bottom feed-rolls has two middle feed-rolls 15, instead of a single middle roll, in order to provide room, between said two middle rolls 15, for the booster- 70 spring 36.

Variations may be resorted to within the scope of the invention, and portions of the improvements may be used without others.

Having thus described my invention, I claim: 75

1. In a typing machine, the combination of a platen-roll, two feed-rolls spaced circumferentially of the platen-roll, an individually pressible supporting device for each feed-roll for pressing the feed-roll against the platen-roll, a draw-spring, and means for connecting said draw-spring to both feed-roll-supporting devices and for regulating its force to regulate the feed-roll pressure, said means including a screw journaled in one of said feed-roll-supporting devices, one end of said spring having a clip holdable by means of the thread of said screw, the other end of said spring being attached to the other feed-roll-supporting device, said clip being withdrawable from the screw-thread for placement in different notches afforded by the latter to thereby quickly vary the stretch and force of the spring, the stretch and force of the spring also being variable by turning said screw and thereby causing said clip to move therealong.
2. In a typing machine, the combination of a revolute platen, two feed-roll sets spaced circumferentially of the platen, an individually pressible, supporting device for each feed-roll set for pressing the latter against the platen, a spring connected across the two feed-roll-supporting devices for pressing both of said feed-roll devices jointly, by spring-flexing pressure applied transversely of said spring at a point intermediate of its connections to said feed-roll-supporting devices, and means operable at will for applying and removing said spring-flexing pressure.
3. In a typing machine, the combination of a revolute platen, two feed-roll sets spaced circumferentially of the platen, an individually pressible, supporting device for each feed-roll set for pressing the latter against the platen, a spring connected across the two feed-roll-supporting devices for pressing both of said feed-roll devices jointly, by spring-flexing pressure applied transversely of said spring at a point intermediate of its connections to said feed-roll-supporting devices, and means operable at will for applying and removing said spring-flexing pressure, said two feed-roll-supporting devices being movable for withdrawing said feed-roll sets from the platen, and said pressure-applying means being yieldable to obviate excessive flexing of said spring when said feed-rolls are withdrawn from said platen while said means have been operated to apply said pressure.
4. In a typing machine having a revolute platen, the combination of a feed-roll co-operative with the platen, pivoted arms spaced along the platen for supporting the feed-roll and pressing it against the platen, an externally screw-threaded cross-rod connected to and extending between said pivoted arms, a draw-spring for pressing said feed-roll against the platen and having one end seated in the cross-rod thread, a said spring extending transversely from the cross-rod to anchoring means for its other end, the stretch and force of said spring being adjustable, for regulating the feed-roll pressure, by locating the first draw-spring end differently along said cross-rod by means of said screw-thread.
5. The invention as set forth in claim 4, said first draw-spring end being withdrawable from the screw-thread for placement at different points therealong, and said threaded cross-rod being rotatable, thereby to cause said screw-thread to adjust said first spring end therealong.
6. In a typing machine, the combination of a revolute platen, two feed-roll sets spaced circumferentially of the platen, two laterally-spaced, a pivoted supporting arms for each feed-roll set, a cross-rod connecting each two arms and spaced from the pivot-axis of said arms, one of said cross-rods being externally screw-threaded right and left, respectively, at two sections of its length, and two draw-springs connected across said cross-rods for pressing said feed-roll sets against said platen, the two draw-springs being respectively seated, at one end, in the right and left threaded sections, the other spring ends being anchored to the other cross-rod, said threaded cross-rod being rotatable, whereupon its right and left threads act to variably and oppositely slant said springs across said cross-rods thereby to vary the stretch and tension of said springs for adjusting the feed-roll pressure, the opposite slanting of the springs acting to neutralize the end thrusts induced in the cross-rods by the slanted springs individually.
7. In a typing machine, the combination of a revolute platen, two feed-roll sets spaced circumferentially of the platen, supporting means for each feed-roll set to press the latter against the platen, and two draw-springs individually connected across the two supporting means for said feed-roll sets for pressing the latter against the platen, said springs having connections whereby they may be adjusted independently to regulate their individual forces for regulating the distribution of feed-roll pressure along the platen, and whereby they may be adjusted jointly to regulate the whole distributed feed-roll pressure.
8. In a typing machine, the combination with the platen-roll, of two feed-roll lines, front and rear, near the bottom of the platen, laterally-spaced rocker-arms for each line of feed-rolls, a cross-rod connecting the rocker-arms that are associated with each line of feed-rolls, each cross-rod being spaced from its rocker-arm axis, and a draw-spring connected across the cross-rods and acting to press both lines of feed-rolls against the platen, one of the rocker-arm-connecting cross-rods having spring-end-receiving stations distributed longitudinally thereof, one end of the draw-spring being differentially locatable by means of said stations, to slant the spring differentially across said cross-rods for adjusting the spring-pressure.
9. In a typing machine, the combination with a platen-roll, of two normally-spring-pressed feed-roll lines spaced circumferentially of the platen, a leaf-spring connected across said two feed-roll lines to serve for pressing both feed-roll lines against the platen, and means settable at will to press against said leaf-spring at a place between said feed-roll lines for optionally augmenting the normal-spring-pressure of both feed-roll lines, said set means being restorable at will for restoring the normal feed-roll pressure.
10. In a typing machine having a platen, the combination of a feed-roll, an externally-threaded rod journaled to extend lengthwise of the feed-roll axis, and a draw-spring having one end anchored and having the other end connected to engage the threads of said rod, said draw-spring acting to press said feed-roll against the platen, the feed-roll pressure being adjustable by changing the stretch of said draw-spring by differentially locating said other end of the spring along said rod by means of said thread, either by turning said rod for micrometric adjustment of said stretch, or by drawing said other spring-end out of one place of engagement with said threads and shifting it to another place.
11. In a typing machine, the combination of a

- platens-roll, two feed-rolls spaced circumferentially of the platen-roll, primary spring-means acting to press said feed-rolls against the platen-roll with ordinary pressure, a secondary spring-device having means, normally in idle condition for both feed-rolls, for pressing both of said feed-rolls simultaneously to apply additional spring-pressure jointly to both of said feed-rolls, and a controller common to said feed-rolls and differentially settable at will to put said additional-pressure-applying means in effective condition for both feed-rolls, or, conversely, to restore said additional-pressure-applying means to said normal idle condition.
15. 12. In a typing machine, the combination with the platen-roll, of two feed-roll lines, front and rear, near the bottom of the platen, laterally-spaced rocker-arms, fulcrumed at a suitable axis, for each line of feed-rolls, two cross-rod, one cross-rod connecting the rocker-arms that are associated with one line of feed-rolls, and the other cross-rod connecting the rocker-arms that are associated with the other line of feed-rolls, each cross-rod being spaced from the companion rocker-arm axis, and a draw-spring connected across the cross-rod and acting to press both lines of feed-rolls against the platen, one of the rocker-arm-connecting cross-rod having an external screw-thread that forms spring-end-receiving stations distributed longitudinally thereof, one end of the draw-spring being retractable from said screw-thread for quick lateral shift of said end from one station to another, to slant the spring differentially across said cross-rod for adjusting the spring-pressure, said screw-threaded rod being rotatable for micrometrically ad-

justing the tension of said draw-spring supplementally to the tension-adjustment obtained by retracting said spring-end from one station and replacing it at another station.

13. In a typewriting machine, the combination with a platen-roll, of a feed-roll, a structure for supporting and pressing said feed-roll against the platen, and a draw-spring having connections enabling it to pull upon said structure and in transverse direction of the feed-roll axis, said connections including a rod having a screw-thread along and by means of which one end of said spring is shiftable laterally to vary the transverse direction in which said spring pulls, and thereby vary its pull to regulate the feed-roll pressure effected by said draw-spring.

14. In a typewriting machine or the like, in combination, a structure adapted to be spring-forced, an externally-threaded screw-rod, and a spring-device cooperating therewith to spring-force said structure, said spring-device including an element having two ends, one end being differentially locatable, relatively to the other, on and along said rod by means of said screw-thread so as to slant said element differentially to said rod and thereby vary the stretch and resultant force of said spring-device, said first-mentioned element-end being adapted to be disengageable from said screw-thread at will for a quick shift to one or another station along said thread, said screw-rod being rotatable to screw-shift said first-mentioned element-end along said thread for regulating micrometrically said stretch and force.

WILLIAM F. HELMOND. 35
